H. L. HARRIS,
TELEPHONE SYSTEM,
APPLICATION FILED DEC. 12, 1913.

1,151,683.

Patented Aug. 31, 1915.

UNITED STATES PATENT OFFICE.

HARVEY L. HARRIS, OF ELYRIA, OHIO, ASSIGNOR TO THE GARFORD MANUFACTURING COMPANY, OF ELYRIA, OHIO, A CORPORATION OF OHIO.

TELEPHONE SYSTEM.

1,151,683.

Specification of Letters Patent. Patented Aug. 31, 1915.

Application filed December 12, 1913. Serial No. 806,144.

To all whom it may concern:

Be it known that I, HARVEY L. HARRIS, a citizen of the United States, residing at Elyria, in the county of Lorain and State of Ohio, have invented certain new and useful Improvements in Telephone Systems; and I do hereby declare the following to be a full, clear, and exact description of the invention, such as will enable others skilled in the art to which it appertains to make and use the same.

My invention relates to telephone systems and I have illustrated the same in connection with a manual system, though I contemplate any use for which it may be employed.

My invention relates more particularly to connecting apparatus which may associate lines of different character or which may be used with lines of different character. For example, where common battery and magneto lines enter the same exchange, in systems of the character to which my invention relates, means are provided to connect a magneto with a common battery line or to connect together either common battery or magneto lines.

As a usual thing in common battery lines cut-off means, such as a cut-off relay, is employed for disassociating the line signaling apparatus from the line, while in magneto lines the same or different means may be employed for this purpose.

One of the objects of my invention is to control this cut-off apparatus over a talking conductor or a portion of a talking conductor, thereby greatly simplifying the telephone system and its operation.

Another object of my invention is to accomplish the above-named objects in connection with what is known in the art as a two-strand common battery line circuit.

Other objects of my invention and the invention itself will be probably better understood from a description of a particular embodiment of my invention, which is illustrated in the drawing.

Figure 1 illustrates diagrammatically an embodiment of my invention. Fig. 2 shows a modification of a line apparatus which may be employed in substitution for the line apparatus shown at C in Fig. 1, for example.

Referring now to the drawing and to the particular embodiment illustrated therein, at A I show telephone line apparatus, at B a

main station and at C second telephone line apparatus. As will be seen the line apparatuses A and C are of different character. Any number of these lines may be employed in the system and they may be of various length and the apparatus constituting the same may be of various kinds. The line here illustrated at C is what is commonly known as a magneto line. It extends from a substation at D through the conductors 1 and 2 to the main station at B, where it terminates in a switch element, here illustrated as a jack including contacts 3, 4 and 5. The substation equipment employed at D is well known and will be well understood by those skilled in the art from the diagrammatic representation. The line signal is shown at 6 and positioned so that the operator can know its actuation. In the form shown this signal is controlled by contacts 3 and 7, though I may employ any suitable arrangement for controlling the signal by the operator.

In the form illustrated I have shown at A what is known as a common battery line. This line leads from substation equipment at E through the conductors 8 and 9 to the main station B, where it terminates in a switch element, such as a jack which may employ contacts 10, 11 and 12. Line signaling mechanism is likewise employed by the line A and is here illustrated as a line lamp 13 and a line relay 14 controlling the same. The line is provided with suitable means for disassociating the line signaling apparatus from the line, here illustrated as a cut-off relay 15. It will be noted that the contact 5 of the jack J of the line C is similar to the contact 12 of the jack J' of the line A.

Suitable means are provided for connecting the lines together, here shown as a cord circuit H, which includes talking strands terminating in switch elements adapted to co-operate with the switch elements of the telephone lines. These elements are illustrated in the drawings as plugs P and P', which may be inserted into the jacks for the purpose of completing the connection between the line and the cord circuit. The plug P includes contacts which are here illustrated, as a tip, 16, a ring-contact 17 and a sleeve-contact 18. The plug P' is likewise provided with a tip-contact 19, a ring-contact 20 and a sleeve-contact 21. In the form

shown, the cord circuit is provided with a talking strand 22, which extends from plug to plug of the cord and with a second strand 210 which extends from plug to plug of the 5 cord.

A plurality of paths for the talking current are provided through the cord, one of which includes the conductors 23, 28 and 25 and the other includes the conductors 26, 44 10 and 27.

A plurality of supervisory signals is provided at one or both ends of the cord circuit. The use of these signals depends upon the character of the line with which the cord 15 is associated. For example, the supervisory lamp 29 is employed when the plug P' is inserted into a jack J' of a common battery line, whereas the drop 30 is employed when such plug is associated with a jack of a 20 magneto line. I provide suitable means for selecting the talking path and the supervisory signal to be employed. In the form shown I use a relay 31 for making both 25 selections. Such selection is controlled by the character of the line with which the plug P' is associated. In the form shown this is accomplished by varying the electrical condition of some part of the line or its switching element. For example, means may be 30 provided for creating an electrical potential upon the contact 12 of the jack J' different from the electrical potential upon the contact 5 of the jack J , so that when the plug is inserted, this difference in potential will 35 control the relay 31.

The invention, its purposes and uses will probably be better understood from a description of the operation of the particular embodiment illustrated.

Suppose that a subscriber upon the line A initiates a call, closing the talking bridge of his apparatus, which will complete a circuit through the line relay 14. This attracts its armature 40, closing a switch 40-41 and 45 completing a circuit through the lamp 13 which is actuated in the presence of the operator, who is thus apprised of the desire of the subscriber at E. The operator connects the cord with the line by inserting the plug 50 P' into the jack J' , completing a circuit from ground 42 through relay 13, conductor 43, contact 12, contact 21, relay 31, conductor 44, battery 45 to ground at 46. The relay 15 will be operated, attracting its armatures 47 55 and 48, interrupting the connection of the line signaling apparatus of the line A with the line and retiring the lamp 13. The relay 31 will also be energized, attracting the armatures 50, 51 and 52. The attraction of the armature 50 disconnects the section 28 60 of the talking strand 22 from the section 23 and connects the section 28 through the switch 53-54 to the section 26 and the contact 21 of the plug, interrupting the connection of the drop 30 with the talking strands

of the cord circuit at the switch 52-55 and connecting the supervisory relay 56 through the switch 52-57 with the line circuit. The switch 51-58 will be closed, completing the connection of the battery 45 to the armature 70 60 of the relay 56. Owing to the fact that the magnet 56 is energized over the following circuit ground 61—magnet 56—contacts 57-52—conductor 63-21-19-10-9—talking set at E—8-48-66-12-21-26—75 31-44-45—ground 46, the switch 60-68 will be opened and the lamp 29 will not be operated. However, when the subscriber retires the substation set this circuit of the magnet 56 will be interrupted and the switch 68-60 will be closed. The lamp 29 will be lighted, giving the supervisory signal, which in this instance will be a disconnect signal.

The contact 12 of jack J' is connected to grounded pole of battery through the conductor 43 and ground 42. Owing to this arrangement the magnet 31 will be operated when the plug P' is inserted into the jack of a common battery line. If the calling line, however, had been a magneto line, no such connection to the magneto line jack would exist, the contact 5 of the line C not being connected to the grounded pole of battery so as to create a circuit for the magnet 31.

The operation of the magnet 31 is thus 95 controlled by the character of the line with which the plug P' is associated. In the form shown the control is exercised by the amount of current flowing through said magnet and as here illustrated, this amount will be zero 100 when the plug P' is connected with the jack of a magneto line.

If the plug P' is connected to the jack of a magneto line, the magnet 31 will not be energized and the talking circuit will include the entire talking strand 22, while the drop signal 30 will be bridged across the line through the switch 52-55.

The operation of the right-hand end of the cord circuit associated with the plug P 110 will be clear from the description of the operation just given, except that when the ringing springs are operated, the generator will be connected to the subscriber's line through the grounded branch 60 including 115 the battery 61 when the plug P is inserted into the jack of a common battery line, the battery 61 being employed to furnish current to hold up the cut-off relay. When connected to a magneto line, the ringing circuit is completed through a switch 70-71.

In Fig. 2 I have illustrated an alternate form of line apparatus which is here illustrated on a magneto line. In this arrangement the contact 5' is connected to ground. 125 The character of the branch 101 is such as to exercise control over the relay 310. In the form shown, the resistance of this branch is made so great that the current flowing there-through will not be sufficient to energize the 130

relay 310 so as to cause it to attract its armatures. In the form shown this branch includes a cut-off relay 100 and the resistance of the branch may be varied by placing 5 therein a resistance device 102.

When the subscriber at the substation X calls in, the drop 103 will be operated. When the plug is inserted into the jack J² a circuit will be completed from ground at 10 104 through 102—100—101—5—the contact 18 of the plug P—conductor 27—relay 310—battery 45 to ground 46. The flow of current will be sufficient to actuate the cut-off relay 100, attracting its armatures 110 and 15 111 and cutting off the device 103 from the line, but the flow of current through this circuit will not be sufficient, owing to the resistance 102, to operate the relay 310. As will readily be understood the contacts 12 20 and 5' will both be connected normally through ground to the battery 45, so that a potential will be created upon each. This potential will be different, however, owing to the resistance device 102.

25 It will be understood that I do not intend to be limited to any particular form of apparatus for varying this potential or to a resistance device separate from the relay, as the same purpose may be accomplished in 30 one way by simply making the winding of the relay 100 greater than that of the relay 15.

It will be apparent to those skilled in the art that either end of the cord circuit may 35 be arranged for connection with a line of either character or the other or to be employed constantly with a line of one character. It will be apparent that other forms of signals and cut-off apparatus may be 40 employed, as well as other forms of apparatus to vary the strength or polarity of the current flowing through the relay 31. In fact, numerous and extensive departures may be made from the form and details of 45 the embodiment here illustrated. I have illustrated this embodiment not with the intention of being limited to the details thereof, but for the purpose of illustrating my invention.

50 I claim:

1. In a telephone system, the combination of a main station, a plurality of telephone lines of diverse character leading to the main station, substation equipment on said 55 lines, line signaling mechanism at the main station associated with the telephone lines, cut-off apparatus for the line signaling mechanism of lines of certain character, connecting apparatus for connecting the lines 60 together including talking strands, said cut-off apparatus being controlled over a talking strand of the connecting apparatus, a plurality of supervisory signals associated with the connecting apparatus and means 65 controlled by the character of the line appa-

ratus to which the connecting apparatus is associated for selecting said supervisory signals.

2. In a telephone system, the combination of a main station, a plurality of substation 70 lines of diverse character leading to the main station, substation equipment on the line, signaling mechanism associated with the lines, cut-off relays for interrupting the association of the line signaling mechanism 75 with lines of a certain character, connecting apparatus at the main station for connecting the lines together, switching mechanism for connecting the connecting apparatus to the telephone lines, a plurality of supervisory signals associated with each switching apparatus, said cut-off relays being controlled over a talking strand of the connecting apparatus and means governed by the character of the line apparatus employed to 80 connect the connecting apparatus to a subscriber's line for selecting the supervisory signals.

3. In a telephone system, the combination of a main station, a plurality of subscriber's 90 lines leading to the main station and terminating in jacks of diverse character at the main station, a cord circuit at the main station for connecting the lines together terminating in plugs to be associated with the 95 jacks of the lines, cut-off relays provided for certain of the telephone lines, circuits for said relays including a talking strand of the cord circuit controlled by said plugs and jacks, a plurality of paths for the voice currents through the cord and means controlled by the character of the line apparatus with 100 which the plug is associated for selecting said talking paths.

4. In a telephone system, the combination of a main station, a common battery line leading to the main station and terminating thereat in a jack of a certain character, a magneto line leading from a substation to the main station and terminating thereat in 110 a jack of a character different from the jack of the common battery line, line signaling apparatus for each line, a cut-off relay for the common battery line, a cord circuit including a plurality of paths for voice currents, said cord circuit terminating in plugs 115 adapted to be inserted into the jacks, said cut-off relay being controlled and operated over a talking strand of the cord circuit and means controlled by the character of the 120 jack into which the plug is inserted for selecting said talking paths.

5. In a telephone system, the combination of a main station, a common battery line leading to the main station and terminating in a jack thereat, line signaling apparatus for the common battery line and a cut-off relay controlling said line signaling apparatus, a magneto line leading to the main 125 station and terminating in a jack thereat 130

- different in character from the jack of the common battery line, substation equipment on each line, a cord circuit at the main station for connecting the lines together including a plurality of paths for talking current, a circuit over which the cut-off relay is operated including a talking strand of the cord circuit, plugs in which said cord circuit terminates, said plugs adapted to be inserted into the jacks, the selection of the path of talking current being controlled by the character of the jack into which the plug is inserted.
6. In a telephone system, the combination of a main station, a plurality of telephone lines leading to the main station, said telephone lines terminating at the main station in jacks of different character, a cord circuit at the main station including a plurality of paths for talking current, three-point plugs in which said cord circuit terminates, each point of each plug being connected to a talking conductor of the cord circuit and means controlled by the character of the jack in which the plug is inserted for selecting the path for the talking current through the cord.
7. In a telephone system, the combination of a main station, a common battery line leading to the main station and terminating in a jack thereat, a magneto line leading to the main station and terminating thereat in a jack of a character different from the jack in which the common battery line terminates, substation equipment on the telephone lines, a cord circuit at the main station including talking conductors, three-point plugs for the cord circuits, each point of each plug connected to a talking conductor of the cord circuit, a plurality of supervisory signals in the cord circuit and means controlled by the character of the jack into which the plug is inserted for selecting the supervisory signals.
8. In a telephone system, the combination of a main station, a telephone line leading to the main station and provided with a jack at said main station, a second telephone line leading to the main station and terminating in a jack thereat, means to cause an electrical potential upon one of the contacts of the jack of the second line different from a similar contact on the jack of the first-named line, a cord circuit for connecting the lines together including talking conductors, said cord circuit terminating in three-point plugs, each of the points of the plugs being connected to a talking conductor, a plurality of supervisory signals associated with a plug and means controlled by the potential of the jack for selecting the supervisory signal to be used.
9. In a telephone system, the combination of a main station, a telephone line leading to the main station and terminating in a jack thereat, substation equipment on the telephone line, a second telephone line leading to the main station and terminating in a jack thereat, a contact on said jack of the second telephone line similar to a contact on the jack of the first-named telephone line, substation equipment on the second telephone line, line signaling mechanism and a cut-off relay therefor associated with the second telephone line, a cord circuit for connecting said telephone lines together including talking strands, a circuit for the cut-off relay including a portion of one of said talking strands, means for creating on a contact of the second line an electrical potential differing from the electrical potential on a similar contact of the first line, a plurality of supervisory signals associated with one end of the cord circuit and means controlled by the potential of the contact of the line jacks for selecting the supervisory signal to be used.
10. In a telephone system, the combination of a main station, a plurality of telephone lines of diverse character leading to the main station, connecting apparatus at the main station for connecting the lines together including talking strands, a plurality of supervisory signals associated with one end of the connecting apparatus and means controlled over a portion of one of the talking strands by the character of the apparatus of the line to which such end of the connecting apparatus is connected for selecting the supervisory signal to be employed.
11. In a telephone system, the combination of a main station, a telephone line leading to the main station and terminating in a jack thereat, substation equipment on the telephone line, a second telephone line leading to the main station and terminating in a jack thereat, substation equipment on the second telephone line, each of said jacks being provided with a contact similar to a contact on the other jack, a cord circuit for connecting the lines together including talking strands, a plurality of supervisory signals associated with one end of the cord circuit, electromagnetic means for selecting the supervisory signal to be used, a circuit for said electromagnetic means including a portion of one of the talking strands and the above mentioned contact of the line jack, means for creating an electrical potential upon the above mentioned contact of the second line different from the electrical potential on the above mentioned contact of the jack of the first-named line, said electromagnetic means being controlled by the electrical potential of such contact.
12. In a telephone system, the combination of a main station, a telephone line leading to the main station and terminating in a jack thereat, substation equipment on the telephone line, a second telephone line lead-

- ing to the main station and terminating in a jack thereat, substation equipment on the second telephone line, the jacks of the first and second line each being provided with a contact similar to the contact on the other jack, a cord circuit for connecting the lines together including talking strands and a plurality of paths for the talking current through the cord circuit, electromagnetic means for selecting the path for the talking current to be employed, a circuit for said electromagnetic means including a talking strand and the aforesaid contact of the jack into which the line is to be inserted, means for creating an electrical potential on the aforesaid contact of the second-named line different from the electrical potential on the similar contact of the first-named line, said relay being controlled by the electrical potential of such contact.
13. In a telephone system, the combination of a main station, a plurality of telephone line apparatus of different character, each of said line apparatus including substation equipment, line conductors and mechanism at the central station, connecting apparatus at the central station including a plurality of talking conductors, a plurality of supervisory signals associated with one end of the connecting apparatus and means for selecting the supervisory signal to be employed, said means controlled over one of said talking conductors by the character of the line apparatus with which the connecting apparatus is associated.
14. In a telephone system, the combination of a main station, a plurality of telephone line apparatus associated with the main station, each telephone line apparatus including substation equipment, line conductors and mechanism at the central station, connecting apparatus for connecting the line apparatus together including a plurality of talking conductors, a plurality of supervisory signals associated with one end of the connecting apparatus and means for selecting the supervisory signal to be employed, said means being controlled over a plurality of talking conductors, a plurality of line apparatus associated with the main station, said line apparatus including substation equipment, line conductors and apparatus at the main station normally associated with the line conductors, connecting apparatus at the main station for connecting the lines together, including a plurality of talking conductors, providing a plurality of paths for voice currents through the connecting apparatus, means for selecting the paths to be employed, said means being controlled over one of said talking conductors by the character of the line apparatus with which the connecting apparatus is associated.
15. In a telephone system, the combination of a main station, a plurality of telephone line apparatus leading to the main station including substation equipment, line conductors and mechanism at the central station normally associated with the line conductors, connecting apparatus at the central station for connecting lines together, a plurality of paths for the voice currents through said connecting apparatus and means for selecting the path to be used, including a portion of one of said talking conductors proper.
16. In a telephone system, the combination of a main station, a plurality of line apparatus of various characters associated with the main station, said line apparatus including substation equipment, line conductors and apparatus at the main station normally associated with the line conductors, connecting apparatus at the main station for connecting the lines together, including a plurality of talking conductors, providing a plurality of paths for voice currents through the connecting apparatus, means for selecting the paths to be employed, said means being controlled over one of said talking conductors by the character of the line apparatus with which the connecting apparatus is associated.

In witness whereof I have affixed my signature in the presence of two witnesses this 6th day of December, 1913.

HARVEY L. HARRIS.
